UNITED STATES PATENT OFFICE.

WILLIAM E. COOK, OF NEW YORK, N. Y.

CARRIER FOR BRAIDING MACHINES.

Application filed May 29, 1926. Serial No. 112,424.

My invention relates to carriers for braiding machines, and more particularly to a construction of carrier particularly adapted for use upon high speed braiding machines, 5 and which will permit the operation of lower speed braiding machines at higher speeds.

Carriers of the type to which my invention relates embody therein a spindle for the cop or bobbin containing the braid or strand, and 10 a traveller or weight for automatically taking up slack created by the sinuous path of travel of the carrier, and acting as the actuating member of a stop mechanism by which the fall of the traveller or weight, as a result 15 of the breakage of the thread or strand, the automatic stoppage of the machine is caused.

Low speed braiders in which carriers of this type are used, are ordinarily operated 20 at 240 R. P. M., speeds in excess of this, resulting in breakage of the thread or strand with a frequency which makes higher speeds of such machines impracticable. This is due in large measure to the inertia of the traveller or weight at the opposite ends of its reciprocation, causing sudden stresses to be applied to the thread or strand when the paying out thereof is required as when the carrier is moving away from the axis about 25 30 which the braid is being formed, or to the creation of slack in the thread or strand as a result of such inertia when the carrier is moving toward said axis, during which time the traveller or weight should be operative 35 to make up such slack.

The difficulties in synchronizing the reciprocatory movement of the traveller or weight with the sinuous movements of the carrier, have resulted in a necessary curtailment 40 in the speed of travel of the carrier, resulting in a necessary curtailment in the output capacity of the braiding machine.

With the above conditions in mind, I have provided a carrier in which the automatic 45 stop mechanism while entirely independent of the traveller, is nevertheless controlled thereby in a manner to permit the automatic stoppage of the machine in the event of sudden and excessive downward movement of the traveller resulting from the 50 breakage of a thread or strand, thus permitting the use of a traveller of very light weight so that the moving inertia thereof

will be reduced to a minimum and a reversal in the direction of movement thereof is 55 permitted without the development of breaking stresses upon the thread or strand. In such a carrier, the traveller may have rapid movement imparted thereto when taking up slack by a spring of very light 60 tension, the compression of this spring when paying out the thread or strand offering insufficient resistance to the upward movement of the traveller to develop such breaking 65 stresses.

Furthermore, with a construction of carrier embodying the invention, the thread or strand at all times will be subjected to substantially uniform tensioning conditions 70 from the traveller.

With a carrier embodying characteristics, such as are above referred to, much higher speeds may be attained in the ordinary braiding machines, such carriers, however, being particularly adapted for use with machines of a construction having a speed two or more times that of the ordinary braider. 75

My invention further contemplates a simple construction and arrangement of parts operative upon the member of the stop mechanism mounted upon the carrier, and the means normally making this member of the stop mechanism inoperative, the mechanism for holding the stop member in its inoperative relation being so constructed 80 and positioned as to cause the release of said member in the event of an excess downward movement of the traveller. In this manner, I am enabled to secure the desired weight and strength in said member of the stop mechanism and yet place no limitation 85 upon the speed of the machine because of conditions arising when the load of this stop member is applied to the thread or strand.

In conjunction with the particular form 90 of stop mechanism and traveller above referred to, I may and preferably provide a tensioning device between the traveller and the cop or bobbin which will ensure a substantially uniform and adjustable tension 100 between the traveller and the cop or bobbin, thus minimizing a tendency of the overrunning of the cop or bobbin.

Heretofore in braiding machines, it has been found impracticable to use full length 105 bobbins or cops as they come from the

spinning frame, the practice having been to rewind the thread or strand upon special short bobbins with a special wind in order to avoid possible entanglement or snarling 5 of the thread or yarn adjacent the bobbin or cop with a resultant breakage thereof and the automatic stoppage of the machine.

In order to effect economy in the operation 10 of abraiding machine, I preferably so construct a braider as to admit of the use of the full length bobbins or cops, by providing a specially constructed guide for the thread or strand between the point of takeoff from the bobbin or cop and the guide or 15 eye leading to the tensioning device, which special guide will compensate for the vertical change in the point of takeoff from the bobbin or cop, and still further minimize likelihood of entanglement or snarling of the 20 thread or strand adjacent the bobbin or cop.

A carrier embodying my invention has other special desirable features of construction contributing toward high efficiency in a braiding machine resulting from its use, all 25 of which will more fully appear hereinafter.

The invention consists primarily in a carrier for braiding machines embodying therein a base, a spindle for a bobbin or cop, a stem, a traveller slidably mounted on said 30 stem, a spring acting to normally force said traveller towards said base, a stop member unconnected with said traveller, and slidably mounted adjacent said base, and a latch member engageable with said stop member, 35 and positioned in operable relation to said traveller, whereby excessive movement of said traveller by said spring will actuate said latch to release said stop member; and in such other novel features of construction 40 and combination of parts as are hereinafter set forth and described, and more particularly pointed out in the claims hereto appended.

Referring to the drawings,

Fig. 1 is a front view of a carrier embodying one form of the invention;

Fig. 2 is a side view thereof;

Fig. 3 is an enlarged perspective view of one form of traveller, latch member and 50 stop member;

Fig. 4 is a view of the lower part of a different form of traveller, latch member and stop member, broken away to disclose the latch member;

Fig. 5 is a side view of Fig. 2; and

Fig. 6 is a detail view of the form of latch member shown in Figs. 4 and 5.

Like numerals refer to like parts throughout the several views.

In the embodiment of the invention 60 shown in the accompanying drawings, the carrier has a base provided with parallel spaced top and bottom plates 10 and 11, a connecting web 12, and a bottom stud 13.

Supported from the top plate 10 of this

base is a spindle 14 for the bobbin or cop. Also supported from said top plate is a stem 15 upon which is slidably mounted a traveller 16 acted upon by a spring 17 having a normal tendency to force the traveller 70 downwardly or towards the top plate 10.

In the form of the invention shown in Figs. 1 to 3, the traveller 16 consists of a tubular member having a spline 18 formed therein co-operating with a keyway 19 in 75 the stem 15 so as to prevent rotative movement of the traveller. Secured to the traveller in any desired manner is a guide loop, or eye 20.

One end of the spring 17 seats upon the 80 top of the traveller 16 and the other end thereof seats upon a pin 21 passing through the stem 15. The upper part of the stem 15 is flattened as shown at 22, and has at the top thereof, a guide eye 23, and toward the 85 bottom of the portion 22 thereof, a pigtail or eye 24. Intermediate the eyes 23 and 24 is an adjustable tensioning device 25 such as is commonly used upon sewing machines, but having a guide eye 25a.

The traveller 16 is made as light as possible with due regard to durability, the spring 17, while of very light tension, being relied upon solely to impart the downward movement to the traveller 16 for taking up 95 slack in the thread or strand.

Upon the side of the spindle 14 opposite to that at which the stem 15 is located, I provide a guide 26 which is of a height corresponding approximately with that of the 100 spindle, said guide having thereon, adjacent the bottom and adjacent the top thereof, stop members 27 and 28 limiting the vertical run of the thread or yarn about said guide.

The mechanisms heretofore described relate to the control of the thread or strand in passing from the bobbin or cop to the point of application thereof to any particular object.

I will now describe those parts of the carrier which, by co-operation with the traveller, are adapted to cause the automatic stoppage of a braiding machine in the event of the breakage of the thread or strand. This 115 mechanism comprises a member 29 slidably mounted upon the stem 15 adjacent the bottom thereof, being guided in its movements by this stem and by guide posts 30 and 31. The general contour of this member 29 as 120 shown, coincides with that commonly used upon carriers in which this member is connected with, or forms an integral part of, the traveller, and therewith acts as a weight for taking up slack in the thread or strand 125 or offers slight resistance to the paying out of the thread or strand according to the movements of the carrier.

By the construction described, the member 29 may be located fairly close to the top 130

plate 10 of the base, and may be made of any desired weight, although its short movement will ensure a setting of the member for actuating the stop mechanism, with a rapidity assuring reliability in the stoppage of the machine, and avoiding possible overrunning of the machine after the breakage of a thread or strand. While the member 29 may be made of any desired weight, the 10 conditions present with a construction like that above described are such that no great weight in the member 29 is required.

Carried by the member 29 is a spring latch member 32 having a bevelled end 33 adapted to engage a keeper 34 upon the stem 15. The bevelled end 33 of the latch member 32 is in the path of movement of a striker member 35 carried by and movable with the traveller 16. The spring latch member 32 may be of very light tension, merely sufficient to maintain its engagement with the stop member or keeper 34 notwithstanding the heavy vibrations to which all parts of the carrier are subjected 25 while in use upon a braiding machine, and particularly upon high speed braiding machines.

In the embodiment of the invention shown in Figs. 4 to 6, the construction is 30 substantially the same as that heretofore described, the differences being merely in the details of the construction of the traveller and the latch mechanism for the stop member 29. In this form of the invention, 35 I provide a substantially flat support 36 for the tensioning mechanism 25, and the guides or eyes 23 and 24 closely adjacent the stem 15. The traveller 16^a has a flattened back portion 16^b having a free sliding fit with the support 36 so as to prevent rotative movement of the member 16^a with relation to the stem 15.

The traveller 16 is U-shaped as shown, so as to provide offset bearings by which it is 40 mounted upon the stem 15 and is provided with a guide or eye 20 the same as the traveller 16. The spring 17 and all parts relating to the control of the vertical reciprocal movements of the member 16^a 45 are the same as heretofore described.

In this form of the invention the stem 15 is slotted as shown at 37, and mounted therein is a spring latch member 38 adapted to pass through the upper bearing opening in the member 29 and have its hooked end 39 engage the undersurface of this member. Intermediate the hooked end 39 of this latch member and the point of its support by the stem 15, I so form the member as to provide 50 a striker portion 40 adapted to be engaged by the traveller 16^a and cause the retraction of the latch member to release the stop member 29. The downward movement of the traveller 16 is arrested by a stop pin 41 carried by the stem 15.

While the form of the invention shown in Figs. 4 to 6 has been found to give satisfactory results, its manufacture is somewhat more difficult and expensive than the form of the invention shown in Figs. 1 to 3, 70 both by reason of the additional number of parts and the structural details of the latch mechanism.

The form of latch mechanism shown in Figs. 4 to 6, when a braiding machine is 75 operated at lower speeds, will hold the member 29 sufficiently firmly to prevent accidental stoppage of the machine as a result of vibrations, but with higher speeds, it is not as reliable as the form of the invention 80 shown in Figs. 1 to 3.

The operation of the herein described machine is substantially as follows:—

As a bobbin or cop is mounted upon the spindle 14, and the thread or strand drawn 85 therefrom and passed about the guide 26 between the stop members 27 and 28 thereon. The end of the thread or strand is then passed through the pigtail or eye 24, through the tensioning device 25 and the eye 20 upon the traveller 16, then upwardly 90 through the eye 25^a and 23 to the point of application to the object upon which the braid is being formed.

In setting the tensioning device 25, care 95 should be taken to substantially balance the resistance offered by this device with the greatest tension developed in the spring 17 by the vertical reciprocatory movement of the traveller 16.

When the cop has thus been properly positioned upon the carrier, the stop member 29 is raised until the latch member 32, in the form of the invention shown in Figs. 1 to 3, engages the keeper 34 to support the 105 member 29 above the top plate 10. When the parts are in this position, the braiding machine may be set in operation, the thread or strand holding the traveller 16 at all times so that the striker member 35 will be 110 maintained out of engaging relation with the latch member 32.

In the form of the invention shown in Figs. 4 to 6, the member 29 is raised until the hooked end 39 of the latch member 38 115 is engaged with the undersurface of the top of the member 29, thus establishing the same conditions as are heretofore referred to in connection with the form of the invention shown in Figs. 1 to 3.

During a normal operation of the machine, the traveller 16, with movement of the carrier away from the point of formation of the braid, will rise against the tension of the spring 17, thus paying out slack 125 between the tensioning device 25 and the object upon which the braid is being formed, the light tension of the spring 17 and the light weight of the traveller offering merely sufficient resistance to the upward move- 130

ment of the traveller to ensure the thread or strand being held sufficiently taut to avoid ballooning of the thread without developing sufficient resistance even at extremely high speeds to cause the breakage of the thread or strand. With the movement of the carrier toward the point of formation of the braid, the slack formed by this movement will be taken up by the downward movement of the traveler 16 under the control of the spring 17, the maximum extent of this movement, however, being insufficient to engage the striker 35 or the traveller 16^a with the latch member 32 or 38. This condition avoids the release of the member 29 under all conditions excepting a breakage of the thread or strand or the exhaustion of a bobbin or cop.

The combined tensioning effect of the spring 17, traveller 16 or 16^a and the tensioning device 25 is such as to permit the gradual feeding of the thread or strand as required in the braiding operation, the traveller taking up any slack which may be formed by the feeding of the thread or strand from the bobbin or cop.

In the event of the breakage of the thread or strand, however, the traveller 16 or 16^a and the spring 17 will be relieved from restraining stresses from the thread or strand between the carrier and the object upon which the braid is being formed, thus permitting the spring to instantly force the traveller downwardly to a point where it will engage and release the latch member 32 or 38, and disengage it from the stop member 29, and permit said member, with a very short movement, to fall to a position where it will engage the co-operating member 40 upon the stop mechanism of the braiding machine and cause the stoppage of the machine without such overrunning thereof as will impair the quality of the work. The short distance which the member 29 has to move to bring it into engaging relation with said stop mechanism of the machine will ensure great rapidity in the setting of the stop mechanism, even though the member 29 may not possess any great amount of weight. The action of the spring 17 will be so rapid that in the event of the breakage of the thread or strand irrespective of the position of the traveller when this breakage occurs, the member 29 will be released substantially instantaneously. The latch mechanism itself is very sensitive, and in either form of the invention shown, a movement of the traveller of a quarter of an inch will be sufficient to disengage it to release the member 29. While I have herein referred to the breakage of the thread or strand as the activating cause of the release of the member 29, it is obvious that the exhaustion of the thread or strand upon the bobbin or cop 65 will have the same effect.

The guide 26 is designed primarily to ensure the smooth running of the thread or strand from any takeoff point upon the bobbin or cop without possibility of entangling or snarling of the thread or strand adjacent the cop, notwithstanding that a full length regularly wound bobbin or cop is used upon the carrier instead of the shorter specially wound bobbins or cops now generally used. The stop members 27 and 28 will limit the vertical run of the thread or strand after leaving the cop, and prevent this thread or strand from forming a loose loop which will pass over the top of the spindle 14^a and form the tangle or snarl above referred to. The guide member 26 and its appurtenances will also minimize likelihood of the escape of the thread or strand from the tensioning device 25, because of the tendency to avoid a rapid change in the angle of the thread between the bobbin or cop and the pigtail or eye 24.

Carriers constructed in accordance with the invention herein described, have been found to permit an increase in the speed of ordinary braiding machines from 240 R. P. M. to 360 R. P. M. with a less frequent breakage of the thread or strand than occurs with a machine using the old style of carriers and operating at lower speed. The carriers, however, are designed particularly for use upon special high speed machines capable of attaining 480 R. P. M. or even higher speeds wherein likelihood of the frequent breakage of the thread or strand is not only very much increased, but in which the tensioning stresses will be very much greater and the time intervals in the movements of the traveller must be very much less.

In a carrier embodying the invention, the traveller 16—16^a is so light as to develop practically no moving inertia sufficient to place any strain upon the thread or strand when reversing the movement of the traveller from a downward to an upward direction, thus permitting a fairly accurate control of the tensioning condition by means of the spring 17. This result is secured without interfering in any way with the stop mechanism of the machine, which, as a result of the unconnected relation of the traveller 16 and the member 29, permits greater reliability in the action of the traveller and of the stop member 29 as well.

It is not my intention to limit the invention to the precise details of construction shown in the drawings, it being apparent that these are subject to wide variation in adapting the carrier embodying the invention to different types of braiding machines with which it is capable of use. In the forms of the invention shown, the construction is that commonly used in low speed braiding machines.

Having described the invention, what I claim as new and desire to have protected by Letters Patent, is:—

1. A carrier for braiding machines embodying therein a base, a spindle for a bobbin or cop, a stem, a traveller slidably mounted on said stem, a spring acting to normally force said traveller towards said base, a stop member unconnected with said traveller, and slidably mounted adjacent said base, and a latch member engageable with said stop member, and positioned in operable relation to said traveller, whereby excessive movement of said traveller by said 15 spring will actuate said latch to release said stop member.
2. A carrier for braiding machines embodying therein a base, a spindle for a bobbin or cop, a stem, a traveller slidably mounted on said stem, an eye upon said traveller, a tensioning device engageable by the thread between said eye and said spindle, an eye above said traveller through which the thread passes, an eye between said 25 tensioning device and said spindle, a spring acting to normally force said traveller towards said base, a stop member unconnected with said traveller, and slidably mounted adjacent said base, and a latch member engageable with said stop member, and positioned in operable relation to said traveller, whereby excessive movement of said traveller by said spring will actuate said latch to release said stop member.
3. A carrier for braiding machines embodying therein a base, a spindle for a bobbin or cop, a stem, a traveller slidably mounted on said stem, an eye upon said traveller, a tensioning device engageable by the thread between said eye and said spindle, an eye above said traveller through which the thread passes, an eye between said 35 tensioning device and said spindle, a coiled spring encircling said stem and acting to normally force said traveller towards said base, a stop member unconnected with said traveller, and slidably mounted adjacent said base, and a latch member engageable with said stop member, and positioned in operable relation to said traveller, whereby excessive movement of said traveller by said 40 spring will actuate said latch to release said stop member.
4. A carrier for braiding machines embodying therein a base, a spindle for a bobbin or cop, a stem positioned at one side of said spindle, a traveller slidably mounted on said stem, a spring acting to normally force said traveller towards said base, a stop member unconnected with said traveller, and slidably mounted adjacent said base, a latch member engageable with said stop member, and positioned in operable relation to said traveller, whereby excessive movement of said traveller by said 45 spring will actuate said latch to release said stop member.
5. A carrier for braiding machines embodying therein a base, a spindle for a bobbin or cop, a stem positioned at one side of said spindle, a traveller slidably mounted on said stem, a spring acting to normally force said traveller towards said base, a stop member unconnected with said traveller, and slidably mounted adjacent said base, a latch member engageable with said stop member, and positioned in operable relation to said traveller, whereby excessive movement of said traveller by said 50 spring will actuate said latch to release said stop member, a guide member positioned upon the other side of said spindle extending for substantially the height of the bobbin or cop about which the thread passes.
6. A carrier for braiding machines embodying therein a base, a spindle for a bobbin or cop, a stem positioned at one side of said spindle, a traveller slidably mounted on said stem, an eye upon said traveller, a tensioning device engageable by the thread between said eye and said spindle, an eye above said traveller through which the thread passes, an eye between said tensioning device and said spindle, a spring acting to normally force said traveller towards said base, a stop member unconnected with said traveller, and slidably mounted adjacent said base, a latch member engageable with said stop member, and positioned in operable relation to said traveller, whereby excessive movement of said traveller by said 55 spring will actuate said latch to release said stop member, and a guide member positioned upon the other side of said spindle extending for substantially the height of the bobbin or cop about which the thread passes.
7. A carrier for braiding machines embodying therein a base, a spindle for a bobbin or cop, a stem having an eye toward the top thereof, a traveller slidably mounted upon said stem, means carried by said stem limiting the upward movement of said traveller, a tensioning device engageable by the thread and positioned between said last named means and the eye at the top of said stem, an eye carried by said stem between said tensioning device and said spindle, a coiled spring encircling said stem bearing against said means so as to normally force said traveller against said base, a stop member unconnected with said traveller slidably mounted upon said stem adjacent said base, supplemental guides for said stop member,

a latch mechanism comprising a spring latch member carried by and movable with said member, and having an inclined portion presented towards said traveller, and a keeper carried by said stem engageable by said latch member, and a striker upon said traveller positioned to engage said spring latch member, whereby excessive movement of said traveller by said spring will cause the release of said stop member.

8. A carrier for braiding machines embodying therein a base, a spindle for a bobbin or cop, a stem having an eye toward the top thereof positioned at one side of said spindle, a traveller slidably mounted upon said stem, means carried by said stem limiting the upward movement of said traveller, a tensioning device engageable by the thread and positioned between said last named means and the eye at the top of said stem, an eye carried by said stem between said tensioning device and said spindle, a coiled spring encircling said stem bearing against said means so as to normally force said

traveller against said base, a stop member 25 unconnected with said traveller slidably mounted upon said stem adjacent said base, supplemental guides for said stop member, a latch mechanism comprising a spring latch member carried by and movable with 30 said member, and having an inclined portion presented towards said traveller, and a keeper carried by said stem engageable by said latch member, a striker upon said traveller positioned to engage said spring 35 latch member, whereby excessive movement of said traveller by said spring will cause the release of said stop member, a guide member positioned upon the other side of said spindle extending for substantially the 40 height of the bobbin or cop about which the thread passes, and stop members carried by said guide member limiting the vertical run of the thread or strand in relation thereto.

In witness whereof I have hereunto af- 45 fixed my signature this 28th day of May, 1926.

WILLIAM E. COOK.
